SPRAYING APPARATUS

Henry E. Brandt, North St. Paul, Minn.

Application March 29, 1937, Serial No. 133,615

12 Claims. (Cl. 221—77)

This invention relates to a sprayer construction and particularly to a sprayer of the type which may be carried by the operator and in which the fluid is placed under pressure by air.

5 It is desirable in such a sprayer to have a receptacle with a rather large opening at its top so that the spraying fluid may be conveniently placed therein. This opening must be closed during the spraying operation and it is desirable to have a 10 simple means and one which may be easily and quickly operated to tightly close the said opening and receptacle. A pump cylinder for pumping air is provided and it is desirable to have the handle which operates the plunger rod of the 15 pump or pump cylinder also used for effecting said closure.

It is an object of this invention, therefore, to provide a simple and efficient type of receptacle adapted to receive the spraying fluid.

20 It is a further object of the invention to provide a receptacle having a comparatively large opening for the reception of the spraying fluid together with simple and easily and quickly operated means for closing said opening.

25 It is still another object of the invention to provide a sprayer having an air pump cylinder with a plunger rod equipped with a handle, said handle also being constructed and arranged to be used in effecting the closure of the receptacle.

30 It is still further an object of the invention to provide a sprayer comprising a receptacle having an opening at its upper end surrounded by a gasket-receiving surface, a closure plate carrying a gasket adapted to engage said plate and rotatable means for pressing said gasket against said surface without rotating said gasket.

These and other objects and advantages of the invention will be fully set forth in the following description made in connection with the accompanying drawings in which like reference characters refer to similar parts throughout the several views and in which:—

Fig. 1 is a perspective view of the sprayer, a portion of the discharge tube and the discharge nozzle being broken away;

Fig. 2 is a view in side elevation of the sprayer with the upper portion thereof shown in central vertical section;

50 Fig. 3 is a partial view in side elevation of the closure means together with a portion of the pump cylinder and the pump plunger rod and handle;

Fig. 4 is a horizontal section taken on line 4—4 55 of Fig. 3 as indicated by the arrows;

Fig. 5 is a horizontal section taken on line 5—5 of Fig. 3 as indicated by the arrows;

Fig. 6 is a partial vertical section similar to Fig. 2 but shown on an enlarged scale indicated by line 6—6 of Fig. 7;

Fig. 7 is a top plan view of the cover clamping plate used; and

Fig. 8 is a top plan view of the container.

Referring to the drawings, a sprayer is shown comprising a receptacle 10 and while various forms of receptacles might be used, in the embodiment of the invention illustrated the receptacle 10 is shown as an upright cylinder having beads 10a adjacent its top and bottom and having a cup-shaped portion 10b at its top. The portion 15 10b is open at its upper end and the side wall thereof forms an upstanding rim, the same being shown as having an outwardly turned bead 10c at its upper edge. A short distance inwardly of the side wall of portion 10b the same is formed 20 with a plurality of partly circular helical flanges 10d, said flanges being partly circular as shown in Fig. 8. The upper part 10e of container 10 upon which portion 10b seats and to which it is secured, extends inwardly horizontally and is provided 25 with a central opening 10f of comparatively large diameter, which opening is surrounded by a bead 10g struck up from portion 10e. A closure plate 11 is provided carrying at its central portion 30 a pump cylinder 12 which extends downwardly below said plate into receptacle 10 and which has its open upper end projecting some distance above said plate, said upper end being provided with an outwardly extending bead 12a. The plate 11 at its outer portion is bent to form an annular 35 trough in which is seated a gasket member 13. The bead 10g forms a gasket-receiving surface or a seat for gasket 13 which engages the same to form a tight closure. A second plate 14 is provided, which plate is formed at its outer edge with 40 a plurality of partly circular helical flanges 14a adapted to cooperate with flanges 10d. It will be seen from Figs. 4 and 8 that said flanges have adjacent ends, the high portion of one flange being adjacent the low portion of the other flange and 45 disposed some distance above the same. With this arrangement the flanges 14a may have their ends enter below the flanges 10d and in the rotation of plate 14 the same will be drawn downwardly toward the receptacle by flanges 10d. 50 Plate 14 engages the top of plate 11 adjacent the outer top portion of the latter and is adapted to press plate 11 downwardly as plate 14 is rotated. Plate 14 has an upwardly pressed central portion 14b forming a substantially cylindrical recess at 55

its lower side adapted to receive the upper end of the pump cylinder 12. The wall surrounding said recess has circumferentially spaced resilient portions 14c separated a distance slightly less than the diameter of the bead 12a. As shown in Fig. 7 these portions are straight portions at opposite sides of portion 14b. The bead 12a and thus the upper end of pump cylinder 12 must be forced past portions 14c with considerable pressure to be received in the recess in portion 14b. The pump cylinder and thus plate 11 are then connected to plate 14 against longitudinal separation or movement by any ordinary force but are rotatable relatively to plate 14. Said parts may be separated by a longitudinal pull thereon with the application of considerable force. Member 14 has a central opening through which extends a plunger rod 15 extending into pump cylinder 12 and which will be provided at its lower end with the usual plunger for the air pump. Rod 15 has a handle 16 secured to its upper end and while this handle might be variously formed, in the embodiment of the invention illustrated it is shown as having upwardly curved sides rectilinear and parallel at their upper portions and connected by horizontal portions 16a. Portions 16a are also shown as connected by a central portion 16b having oppositely disposed concave sides. Plate 14 at either side of rod 15 has curved slots 14d, the same having at their centers outwardly extending enlargements 14c. The top of portion 14b is also pressed upwardly at portions 14f at the ends of said slots and at their outer sides to form small recesses on the underside of said portion. Handle 16 has projecting downwardly from its lower side at each side of rod 15, lugs 16c and these lugs have outwardly extending portions or projections 16d with flat top surfaces. In Fig. 1 the sprayer is shown as having small brackets 17 secured in vertically spaced relation along one side in which are connected the rings 18, in turn pivotally connected to clips 19 secured to the ends of a supporting strap 20 which the operator may place around his shoulders. A portion of the discharge tube 21 for the sprayer is also shown in Fig. 1.

In operation, when the sprayer is to receive the spraying fluid, the lugs 16c will be placed downwardly through the slots 14d through portions 14e. Handle 16 will then be rotated in a counter-clockwise direction and the projections 16d will move under the top of portion 14b and said lugs will engage the ends of slots 14d and rotate plate 14. Said plate will be rotated to bring the helical flanges 14a out of engagement with the flanges on the top of container 10. Handle 16 will then be lifted and at this time the projections 16d will seat in the recesses formed at the undersides of portions 14f. Plate 14 and plate 11, which, as stated, is connected thereto, will now be lifted and removed together with pump cylinder 12. The spraying fluid can now be poured into opening 10f. When the desired amount of fluid has been placed in the container the plates 11 and 14 together with pump cylinder 12 will be again placed in position with gasket 13 engaging the bead 10g. Handle 16 will now be rotated in a clockwise direction and the lugs 16c will engage the other ends of slots 14d and plate 14 will be rotated. The flanges 14a will move under flanges 10d and due to the helical formation of these flanges plate 14 will be drawn downwardly toward the container and this plate will press upon plate 11 so that plate 11 will be moved downwardly and gasket 13 will be pressed tight against the bead or surface

16g. Owing to the provision for relative rotation between the upper end of the pump cylinder and plate 14 the plate 11 need not rotate so that there will be no rotation of gasket 13. This is desirable as it is objectionable to rotate the gasket on its seat. The sprayer is now tightly closed and the desired air pressure can be placed on the liquid by slightly rotating handle 16 so that the lugs 16c can be withdrawn through slots 14d and enlargements 14e and the handle then reciprocated to pump the air through cylinder 12 and into the receptacle 10. After the desired air pressure has been attained the handle 16 can again be moved to insert lugs 16c through the slots 14d and said lugs may be moved to the ends of said slots. The sprayer can then be carried by means of handle 16 if desired. The member 16b forms in effect a funnel and prevents spilling of any liquid which might not at once enter the opening 10f. The portion 16b being permanently secured to the container is always available and a funnel is always thus in place for use.

From the above description it is seen that applicant has provided a very simple and efficient structure of sprayer and particularly of the closure means for the sprayer. The structure is very compact and comprises very few parts. The filling of the container can be easily and quickly done and the sprayer quickly put in condition for use. The device has been amply demonstrated in actual practice and found to be very successful and efficient.

It will, of course, be understood that various changes may be made in the form, details, arrangement and proportions of the parts, without departing from the scope of applicant's invention, which generally stated, consists in a device capable of carrying out the objects above set forth in the parts and combinations of parts disclosed and defined in the appended claims.

What is claimed is:—

1. In a sprayer construction, a receptacle having a central opening at its upper end surrounded by a surface adapted to form a seat for a gasket, a closure plate for said opening carrying a gasket engageable with said surface and having a pump cylinder extending downwardly therefrom, a rotatable member above said first mentioned plate having clamping means thereon, means on said receptacle surrounding said opening adapted to be engaged by said rotatable clamping means and means including a handle for rotating said member to cause said clamping means to draw it toward said receptacle and press said gasket against said surface, said member and first mentioned plate being attached relatively rotatable so that said gasket is not rotated with said member and a plunger in said pump cylinder reciprocable by said handle for pumping air into said receptacle.

2. In a sprayer construction, a receptacle having a central opening at its upper end surrounded by a surface adapted to form a seat for a gasket, a closure plate for said opening carrying a gasket engageable with said surface and having a pump cylinder carried thereby, a second plate above said first mentioned plate having a rotatable clamping means thereon, means on said receptacle surrounding said opening adapted to be engaged by said clamping means, a handle for rotating said second plate to cause said clamping means to draw it toward said receptacle and press said first mentioned plate toward said receptacle and press said gasket against said surface, said second plate being connected to said first mentioned plate against longitudinal movement but being rotat-

able relatively thereto so that said gasket is not rotated with said second plate but said first mentioned plate may be lifted by said second plate and a plunger in said cylinder reciprocable by said handle for pumping air into said receptacle.

5 3. In a sprayer construction, a receptacle having a central opening at its upper end surrounded by a surface adapted to form a seat for a gasket, a closure plate for said opening carrying a gasket engageable with said surface and having a pump cylinder extending downwardly therefrom, a second plate above said first mentioned plate having a rotatable clamping means thereon, means on said receptacle surrounding said opening adapted to be engaged by said clamping means, a handle for rotating said second plate to cause said clamping means to draw it toward said receptacle, press said first mentioned plate toward said receptacle and press said gasket against said surface, said second plate having a central raised portion forming a cylindrical recess, said pump cylinder having its upper open end projecting above said first mentioned plate and receivable in said recess, said end of said pump cylinder and first mentioned plate being connected to permit relative rotative movement thereof and a plunger in said cylinder reciprocable by said handle for pumping air into said receptacle.

20 4. In a sprayer construction, a receptacle having a central opening at its upper end surrounded by a surface adapted to form a seat for a gasket, a closure plate for said opening carrying a gasket engageable with said surface and having a pump cylinder in the center thereof and extending downwardly therefrom, the open top of said cylinder extending above said plate, a second plate having a central recess therein into which said end of said pump cylinder extends, means connecting said pump cylinder and second plate preventing relative longitudinal movement of said plates but permitting relative rotative movement thereof, a plurality of helical flanges on said receptacle surrounding said opening, each less than 180 degrees in extent, similar helical flanges on said second plate, a plunger rod for said cylinder extending through said second plate, a handle at the top of said rod having means detachably engaging said second plate for rotating the same to engage said flanges and draw said first mentioned plate toward said container and press said gasket against said surface and a plunger in said cylinder reciprocable by said handle for pumping air into said receptacle.

25 5. A sprayer construction comprising a receptacle having a rigid top with an upstanding outer rim forming in effect a funnel, a plurality of partly circular helical flanges within said rim, said container having a central opening and a gasket-receiving surface surrounding said opening and disposed between the same and said flanges, a cover plate for said opening having a gasket therein engageable with said surface, a second plate having a plurality of partly circular helical flanges adapted to engage said first mentioned flanges and draw said first mentioned plate toward said receptacle in the relative rotation of said respective helical flanges and press said gasket against said surface, said second plate being rotatable relative to said first mentioned plate and means for rotating said second plate.

30 6. In a sprayer construction, a receptacle having a central opening at its upper end surrounded by a surface adapted to form a seat for a gasket, a closure plate for said opening carrying a gasket engageable with said surface and having a mem-

ber extending downwardly therefrom adapted to pass through said opening and be disposed in said receptacle, a second plate above said first mentioned plate having clamping means thereon, means on said receptacle surrounding said opening adapted to be engaged by said clamping means, said clamping means being relatively rotatable while in engagement to move said plates downwardly and press said gasket against said surface, said second plate having a central upwardly pressed portion forming a recess therein and having oppositely disposed slots in the top thereof, a handle having lugs receivable in said slots with projections adapted to extend outwardly beyond said slots so as to lift said second plate, said lugs being also adapted to engage the ends of said slots to rotate said second plate, said second plate and member being liftable out of said receptacle by said handle.

35 7. A sprayer construction having in combination, a receptacle having a circular opening at its upper end, a surface surrounding said opening adapted to form a seat for a gasket, a closure plate carrying a gasket adapted to engage said surface, a pump cylinder carried centrally of said plate, the upper end of said cylinder projecting above said plate, a second plate having a central recess therein, said pump cylinder having a bead about its upper end, said upper end being movable into said recess, the walls of said recess having circumferentially spaced resilient portions past which said upper end of said cylinder must be forced to enter said recess so that said pump cylinder is connected to said second plate against ordinary longitudinal stress but may rotate relatively thereto and means for moving said first mentioned plate toward said receptacle by said first mentioned plate to press said gasket against said surface.

40 8. In a sprayer construction, a receptacle having a central opening at its upper end surrounded by a surface adapted to form a seat for a gasket, a closure plate for said opening carrying a gasket engageable with said surface and having a pump cylinder extending downwardly and centrally therefrom arranged to be disposed in said receptacle, a member above said first mentioned plate having clamping means thereon, means on said receptacle surrounding said opening adapted to be engaged by said clamping means and means including a handle for rotating said member to relatively rotate said clamping means while in engagement to draw said member toward said receptacle and press said gasket against said surface, said pump cylinder and plate being connected to said member for rotation relatively thereto and being separable therefrom by a forceful longitudinal movement and a plunger in said pump cylinder reciprocable by said handle to pump air into said receptacle.

45 9. A sprayer construction having in combination, a receptacle having a central opening at its upper end surrounded by a surface adapted to form a seal, a closure plate for said opening carrying a portion engageable with said surface and having a pump cylinder carried thereby, a second plate above said first mentioned plate having a rotatable clamping means thereon, means on said receptacle surrounding said opening constituting a cooperating clamping means adapted to be engaged by said first mentioned clamping means, a handle for rotating said second plate to relatively rotate said respective clamping means while engaged to draw said second plate toward said receptacle and press said first men-

tioned plate toward said surface and a plunger in said cylinder reciprocable by said handle for pumping air into said receptacle.

10. A pump cylinder and closure structure for a sprayer comprising a closure plate, a pump cylinder secured to said plate and extending downwardly therefrom, a second plate above said closure plate having a central recess therein, said pump cylinder having a bead about its upper end disposed in said recess and rotatable therein, the wall of said recess extending under said bead so that said pump cylinder is connected to said second plate against movement longitudinally of said pump cylinder but is rotatable relatively to said second plate.

11. In a sprayer construction a receptacle having a central opening at its upper end surrounded by a surface adapted to form a seat for a gasket, a gasket on said seat, said gasket being disposed above the portion of the top of said receptacle adjacent said opening, a closure member for said opening, a pump cylinder centrally secured to said member and carried thereby, said cylinder having an outwardly extending flange thereon adapted to engage said gasket and be pressed thereagainst when said member is in operative position, said member having helical flanges or threads at its periphery, threads or flanges carried by said receptacle outwardly of said first mentioned flange cooperating with said first mentioned threads or flanges, to move said member to operative position when rotated, a plunger rod extending into said cylinder, said member having a central aperture through which said rod extends, a handle at the upper end of said rod having means for detachably engaging said member to rotate the same, said receptacle having an upwardly extending flange forming a funnel for directing fluid into said first mentioned opening.

ing a central aperture through which said rod extends, a handle at the upper end of said rod having means for detachably engaging said member to rotate the same, said receptacle having an upwardly extending flange forming a funnel for directing fluid into said first mentioned opening.

12. In a sprayer construction a receptacle having a central opening at its upper end surrounded by a surface adapted to form a seat for a gasket, a gasket on said seat, a closure member for said opening, a pump cylinder centrally secured to said member and carried thereby, said cylinder having an outwardly extending flange thereon adapted to engage said gasket and be pressed thereagainst when said member is in operative position, said pump cylinder being connected at its upper end to said member and said flange on said cylinder being disposed some distance below the top of said cylinder, said member having helical flanges or threads at its periphery, threads or flanges carried by said receptacle outwardly of said first mentioned flange cooperating with said first mentioned threads or flanges, to move said member to operative position when rotated, a plunger rod extending into said cylinder, said member having a central aperture through which said rod extends, a handle at the upper end of said rod having means for detachably engaging said member to rotate the same, said receptacle having an upwardly extending flange forming a funnel for directing fluid into said first mentioned opening.

HENRY E. BRANDT.
